Patented Dec. 17, 1918.

UNITED STATES PATENT OFFICE.

GEORGE EBER, OF SAN DIEGO, CALIFORNIA.

SIDE EXTENSION FOR CAMPING OUTFITS.

1,287,925.

Specification of Letters Patent. Patented Dec. 17, 1918.

Application filed May 20, 1918. Serial No. 235,606.

To all whom it may concern:

Be it known that I, GEORGE EBER, a citizen of the United States, and a resident of San Diego, in the county of San Diego, and State of California, have invented a new and useful Side Extension for Camping Outfits, of which the following is a specification.

My invention relates to collapsible side extensions for use with camping outfits for automobiles more especially for my camping attachment for automobiles described in my application for patent filed April 30, 1917, Serial No. 165,398.

The object of the present invention is the provision of a side extension constructed of parts which may be taken down and stored away when traveling and which may be assembled with ease when said extension is desired to increase the sleeping accommodations of the apartment on which it is used.

In the accompanying drawings, which are for illustrative purposes, I show the preferred form of my invention, it being understood that changes in the precise construction shown may be made within the scope of what hereinafter is claimed without departing from the spirit of the invention.

Figure 1 is a fragmentary rear view of the front apartment of my camping attachment for automobiles above referred to, showing the present invention thereon, one extension being assembled in operative position; Fig. 2 an elevation of an angle iron 1 and the floor 2 thereon; Fig. 3, a right side elevation of Fig. 1; Fig. 4, a section on the line A—B of Fig. 3, showing both screen frames 6 secured to the bows and box portion; Fig. 5, a plan view of the assembled device, detached from the apartment, partly broken away; Fig. 6, a plan view of the loop 3 and a fragment of the angle iron 1, drawn to an enlarged scale; and Fig. 7, a side elevation of Fig. 6.

Similar reference characters refer to like parts throughout the several views.

The reference numeral 60 denotes the box portion of the front apartment of my camping attachment for automobiles referred to above; 8, the rear end bow and 10, the front end bow of said apartment.

The present invention comprises the loops 3, mounted on said box portion 60; angle

irons 1, hooked into said loops; arms 4 having the lower ends hooked on the pins 11 in the angle irons 1 and the upper ends hooked on the pins 12 in the bows 8 and 10; a floor 2 disposed on said angle irons 1; a vertically disposed screen frame 6, having face pieces 18 on the ends thereof, disposed on the edge of said floor and supported at the top by the arms 5; and the curtains 30 and 50.

The device is assembled as follows: The angle irons 1 are hooked into the loops 3, the arms 4 are hooked in position as shown in the drawing, the floor 2 is laid upon the angle irons 1, the bolts 9 are withdrawn, the frame 6 is removed to the edge of the floor 2 and the floor 2 is pushed against the box portion 60, the arms 5 are hooked in position as shown and the curtain 50 is rolled over the top and dropped down the ends. The curtain 30 is rolled down over the screen when desired.

When it is desired to resume traveling the device is taken down and the parts stored away except the screen frames 6 which are bolted to the box 60 and the bows 8 and 10 as shown. The end flaps of the curtain 50 are folded back on top of the roof and rolled up with the top portion as shown in the drawings.

What I claim and desire to secure by Letters Patent is:

A side extension of the class described, in combination with a camping apartment having a box portion, said box portion having bows mounted thereon; loops mounted on said box portion; angle irons having hooks thereon and hooked in said loops; obliquely disposed bracket arms hooked to said angle irons and to the end bows of said apartment whereby said angle irons are held horizontal; a floor disposed on said angle irons; a vertically disposed screen frame mounted at the outer edge of said floor; and braces connecting the top of said frame with the bows of said apartment; for the purposes set forth.

In testimony whereof I have hereunto signed my name in the presence of two witnesses, this 9th day of May 1918.

GEORGE EBER.

Witnesses:

O. B. PALMER,
R. L. McVEIGH.
